CLAIM

The ornamental design for a shock wave machine as shown and described.

DESCRIPTION

FIG. 1 is a top front perspective view of a shock wave machine showing my new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof;

FIG. 8 is a top rear perspective view thereof; and,

FIG. 9 is an enlarged view of the encircled portion 9 in FIG. 3.

In the drawings, the equal-length broken lines depict portions of the shock wave machine that form no part of the claimed design.

1 Claim, 7 Drawing Sheets
